UNITED STATES PATENT OFFICE

91,962

DESIGN FOR A RADIO PROGRAM REMINDER

Herbert L. Pawliger, New York, N. Y.

Application June 2, 1933, Serial No. 48,260

Term of patent 7 years

To all whom it may concern:

Be it known that I, HERBERT L. PAWLIGER, a citizen of the United States, residing at New York city, in the county of New York and State of New York, have invented a new, original, and ornamental Design for Radio Program Reminders, of which the following is a specification, reference being had to the accompanying drawing, forming a part thereof.

Fig. 1 is a perspective view of a radio program reminder showing my new design.

Fig. 2 is an enlarged end elevational view of the same.

Fig. 3 is a fragmentary plan view of the same, a portion of the device being broken away for convenience in illustrating.

I claim:

The ornamental design for a radio program reminder as shown.

In testimony whereof I have affixed my signature.

HERBERT L. PAWLIGER.
